UNITED STATES PATENT OFFICE.

BYRON E. OSBORN, OF AUBURN, NEW YORK.

ELECTRIC-RAILWAY SYSTEM.

SPECIFICATION forming part of Letters Patent No. 661,020, dated October 30, 1900.

Application filed April 5, 1900. Serial No. 11,729. (No model.)

To all whom it may concern:

Be it known that I, BYRON E. OSBORN, a citizen of the United States, residing at Auburn, in the county of Cayuga and State of New York, have invented certain new and useful Improvements in Electric-Railway Systems; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in electric-railway systems, and especially to a subway or surface system in which a prime conductor suitably insulated from all exterior conducting agents is provided which is designed to carry the electric energy, while mechanical means is utilized for bringing the current to the surface, as required, to energize a normally-dead contact-stand bearing a switch, which when operated by a conductor-shoe carried by the frame of a car-truck allows the current to pass from the prime conductor to and through the contact-stand, thence through the conductor-shoe and conducting-wire to the rheostat or controller on the car, whence it is switched onto the car-motors and returned from the latter through suitable insulated wire to the negative pole of the generator. By returning the current through a suitable conducting medium to the negative pole of the generator instead of through the axle, wheels, rails, and the earth wandering currents are prevented, which in the common construction of electric railways causes electrolysis to grounded metallic pipes.

The invention relates, further, to an electric-railway system which is adapted to the various conditions of city and country lines and in which the wires and electric equipment are inaccessible to pedestrians, thus reducing accidents incident to persons or animals coming in contact with exposed wires to a minimum.

In carrying out my invention I provide at intervals a series of contact-stands which are normally "dead," each stand carrying an oscillating lever which is thrown into contact

with a prime conductor, as a shoe, carried by a car, depresses the lever, whereby the electrical current is communicated to and through a motor on the car and thence returned through a suitable conducting-wire to the negative pole of the generator.

Other features of the present invention will be hereinafter fully described and specifically claimed, as well as the various combinations of coacting elements of the system.

My invention is clearly illustrated in the accompanying drawings, which, with the letters of reference marked thereon, form a part of this application, and in which drawings similar letters of reference marked thereon indicate like parts throughout the several views, in which—

Figure 1 is a plan view of a section of a railway-track, showing the electrical conductor-wires, pipes protecting the latter, and the contact-stands arranged at intervals apart adjacent to the rails. Fig. 2 is a side elevation of one of the contact-stands, parts being in section, and a section of a contact-shoe, shown in dotted lines, which is carried by a car. Fig. 3 is a vertical cross-sectional view through one of the contact-stands and the primary and feeding wires. Fig. 4 is a side elevation of a car carrying motor, controller, and shoe, showing electrical connections between shoe, controller, and motor, said view showing parts in section. Fig. 5 is a side elevation of a portion of a shoe and a contact-stand having an electrical connection with a return conducting-wire, said shoe being shown as in contact with the stand, parts being shown in section. Fig. 6 is a top plan view of a motor on the truck of a car, showing also the track and conducting-wires and generator. Fig. 7 is a vertical longitudinal section through a stand, slightly modified. Fig. 8 is a cross-sectional view of guards shown as held against a contact-stand, and Fig. 9 is a perspective view of the guard and stand shown in Fig. 8. Fig. 10 is a top plan view of a stand and guard-plate.

Reference now being had to the details of the drawings by letter, A designates the prime conducting-wire, which is carried in suitable insulating-piping C, and in the event of the current being conveyed a considerable distance a second feed-wire B is provided which

is also insulated and carried within the piping C, and at any intervals along the route said prime conductor may be united or yoked to the feed-wire, which latter is connected to the 5 positive pole of the generator A'. This tubing is preferably secured to the ties of the railway and at intervals, nearly the length of an ordinary street-car, are secured the conductor-stands D², which are fastened to planks 10 or plates resting on the ties and held thereto by any suitable means. The piping referred to, through which the primary and feeding wires pass, is made up of sections extending from one conductor-stand to another along 15 the side of the rails, and the ends of said wires protrude a few inches beyond the end of the pipe. These exposed ends of the wires are inserted into a coupling A², in which coupling is also held one end of the segmentary conductor I, which is located within the chamber 20 of the contact-stand. To the opposite end of the segmentary conductor a coupling is connected to which the protruding ends of a section of the prime conducting-wire and feeding-wire are held, the latter being contained 25 within another section of piping extending to the next conductor-stand, the entire length of the prime conductor and feeding-wire being made up of similar sections connected as 30 described. At each end of every contact-stand a wooden plank Z, first covered by any suitable cement, as white and red lead in oil, is bolted to the plank or plate on which the contact-stand is held, which plank covers the ends of 35 the wires and pipe, thus making the stand-chamber and pipe water-tight. These contact-stands, which are commonly placed a distance apart equal to nearly the length of a car, may be placed nearer together on curves in order 40 to allow a contact to be made between said stands and a conductor-shoe carried by a car. Said stands are constructed the height of the rails used in the construction of the road, and in the chambered portion of each stand in a 45 system equipped for a city or thoroughfare line is journaled an oscillating contact-lever D, which turns on a stud D'. Loosely journaled on the spindle d, between the upper pivotal ends of said lever, is an antifriction- 50 roller M², and projecting below the stud D' is a portion of said lever which has laterally-extending lugs M.

J and J' are two clamping-plates held in any suitable manner to the segmentary conductor, and on said plate J' are pivoted the 55 lower ends of the angle contact members K and K², as shown clearly in Fig. 2 of the drawings. In order to hold these contact members normally out of contact with the inner 60 wall of the chamber of the stand, springs K³ are utilized, or weights may be used, if desired, the upper ends of the springs being fastened to the angle contact members, while their 65 other ends are connected to the clamping-plate J'. For holding the contact-lever D normally in a vertical relation springs O are held under the lugs M on the opposite sides

of the projecting end of the lever D. In projecting portions of the stand, on its upper edge, are journaled the antifriction-rollers P 70 and P', against which the shoe N contacts as it traverses the stand.

The construction of stand illustrated in Fig. 2, which has been described, is found to be the best form of contact mechanism in a 75 system adapted for grades or for hauling freight, in which a large amperage is required, in which stand contact may be had with the shoe at three different locations.

In systems requiring only a medium amperage the form of stand and contact mechanism illustrated in Fig. 7 I wish to employ. In this slightly-modified construction the shapes of the contact members K and K² instead of being angular and pivoted at their 85 lower ends to the clamping-plate J' are journaled on the studs K³, carried by the walls of the contact-stand, and to one arm of each 90 of said members K and K² is connected a spring K⁴, adapted to normally hold each 95 member in the position assumed by contact member K² in Fig. 7. Instead of the clamping-plate J', Fig. 2, I employ the cups E, which are mounted on plates E', which are clamped to the segmentary conductor I, and these cups 100 are designed to contain metallic mercury.

In Fig. 7 of the drawings one arm of the contact member K is shown as depressed into the receptacle or cup, said member being depressed by the shoe of the car oscillating the 105 contact-lever, which in turn tilts said member K. In this construction, requiring but a medium amount of amperage, the antifriction contact-rollers P and P' may be dispensed with and only the oscillating lever carrying the 110 loosely-journaled contact-roller M² utilized.

The contact-stands which are utilized in the return-circuit and on interurban railways, on which latter there is but little travel other than by the electric cars, the stands being 115 separated beyond the reach of animals or persons, are preferably constructed as shown in Fig. 5. In this stand D³ are mounted the antifriction-rollers P and P', and instead of the oscillating contact-lever, as before described in connection with the stands D², I employ a segmentary conductor I², inserted 120 in the couplings H, which also receive the ends of the return conducting-wire sections G, passing through the insulating-pipes G'. To these couplings are secured the ends of the conductor Y, which is held near the middle 125 of the stand, as illustrated. This return conducting-wire may be made continuous from the negative pole of the dynamo to the extremities of the road or made sectional and connected, as shown, and the stand D³ is "live" normally with the wire to which it is attached.

For protecting the contact-stands I utilize 130 the metallic guards R, (Shown in Figs. 8 to 10, inclusive.) A suitably-recessed portion R' of each of said guard-plates is provided to allow the oscillating contact-lever to operate freely,

and the under edge of each plate is recessed out, as at R², so as to allow any dust or foreign matter which might drop into the recesses R' to escape onto the ground. These

5 guard-plates are preferably bolted to the stands on their outer faces, while the outer faces of the rails will serve to protect the inner faces of the stands.

Referring to Fig. 4 of the drawings, the shoe 10 N is made preferably of two complementary plates of rolled metal, (this detail being better shown in section in Fig. 8,) bolted or otherwise secured together and carrying a binding-post N². By means of brackets N³ a flanged 15 disk N⁴ is held to the shoe sections, and on said disk the metallic post Q rests, said post being connected at its upper end to the frame U of the car. A spring N⁵ is interposed between said disk N⁴ and the frame of the car, 20 whereby the shoe will be self-adjusting, and should the car leave the track accidentally said conductor would be raised several inches, contracting the spring. The ends of the conductor are preferably slightly upwardly 25 turned, so as not to be interfered with in case any foreign matter should happen to be upon the stands.

To the binding post N² is electrically connected one end of the wire N⁶, which has its 30 other end connected to the rheostat or controller T, mounted on the platform of the car. The motor W, carried by the framework of the truck, has geared connection with the driving-wheel W', suitably mounted on the 35 axle W², and a wire T² connects the rheostat or controller with the negative pole of the motor, while the positive pole of said motor is connected by wire T³ to the binding-post T⁴, through which the current passes to the shoe 40 on the opposite side of the car and which is held in contact with the stands in the return-circuit. The lights S in the car are brought into the circuit by means of the connecting-wire S', connecting the switch S² with the conducting-wire N⁶.

In operation, as a car equipped with a shoe on either side substantially the length of the car rests on the rails said shoes will always be held in contact with a contact-stand on the 50 outgoing circuit on the one side and with a contact-stand in the return-circuit on the opposite side. Said stands being disposed in a zigzag relation in the two series with relation to one another and of such a distance diagonally apart, preferably about thirteen feet, will 55 also render the exposed stands safe from contact simultaneously by persons or animals. As the shoe comes in contact with the anti-frictional roller on the oscillating lever the latter is tilted and electrical contact is made and the current passes through the shoe and to the motor, and thence returns to the generator in the manner hereinbefore described.

What I claim is—

65 1. In an electric-railway system, two series of contact-stands disposed at intervals to one another on opposite sides of a railway, a prime

conductor passing through one series of said stands which are normally "dead," an oscillating contact-lever normally "dead," carried by each of the latter, contact members having electrical connection with the prime conductor, shoes carried by a car, one of which shoes being designed, as it traverses a contact-stand through which the primary conductor passes, to tilt said oscillating lever against one of said contact members, and hold the latter against the contact-stand, the second shoe adapted to contact with a stand in the return-circuit, a motor and electrical 80 connections between same and the shoes, as set forth. 70 75

2. In an electric-railway system, two series of contact-stands disposed at intervals to one another on opposite sides of a railway, a prime 85 conductor passing through one series of said stands which are normally "dead," oscillating contact-levers carried by the latter, spring-actuated contact-pieces connected to the primary conductor, the shoes carried by the car, 90 one of which shoes being designed, as it traverses a contact-stand, through which said primary conductor passes, to throw a lever into electrical connection with one of said contact-pieces, the second shoe designed to contact a 95 stand on the opposite side of the railway and in a return-circuit, a motor and electrical connections between same and said shoes, as set forth.

3. In an electrical-railway system, two series of contact-stands disposed at intervals to one another on opposite sides of a railway, a prime conductor passing through one of said series of stands which are normally "dead," oscillating contact-levers carried by the latter, springs for holding said levers in vertical positions, spring-actuated contact-pieces designed to be thrown into electrical connection with the primary conductor as said lever is tilted, a shoe carried by a car and designed to traverse the stands through which the primary conductor passes, and to tilt said levers, a shoe contacting with a stand on the opposite side of the railway, the motor and electrical connections between same and said 110 115 shoes, as set forth. 100 105

4. In an electric-railway system, two series of conductor-stands disposed at intervals to one another, on opposite sides of a railway, in alternate relation, a prime conductor passing through one of said series of stands which are normally "dead," oscillating levers journaled in the latter, pivoted and spring-actuated contact members adapted to be tilted by said levers, the cups held in contact with the primary conductor, and containing metallic mercury, into which the ends of said members are inserted as they are tilted by a shoe traversing the stand and oscillating said lever, the motor, shoes and electrical connections as set forth. 125 130

5. In an electric-railway system, two series of conductor-stands, one series being located along each side of the railway, and in alter-

4
nate relation to one another, a prime conductor and a feeding-wire insulated in suitable piping, and disposed between the stands on one side of the railway, which stands are normally "dead," segmentary conductors located in said stands, couplings connecting the primary conductor to said segmentary conductor, the contact-plates secured to the latter, the oscillating lever pivoted to the stand and spring-actuated, the contact members also spring-actuated and designed to be tilted by said lever into electrical connection with said segmentary conductor, the antifriction-roller carried by said lever, the antifriction-rollers on the stands, the shoes, motor and electrical connections between the latter and said shoes as set forth.

6. A contact-stand for an electric-railway system, comprising the oscillating contact-lever pivoted to the walls of the stand and having an antifriction-roller for contact with a shoe, lugs on the lower end of said lever, springs engaging said lugs to hold said lever normally in a vertical position, the segmentary conductor in the chamber of the stand, the pivoted and spring-actuated contact members, the plates secured to said segmentary conductors, as set forth.

7. In an electric-railway system, a return contact-stand comprising a segmentary conductor carried in the chamber of the stand,

couplings in which the ends of said conductor are held, the antifriction-rollers journaled in the upper edge of the stand, the conductor bolted to the upper edge of the stand and connected to the return-wire, said stand being normally "live" with the wire to which it is connected. 35

8. In an electric-railway system, the combination with the contact-stands, as described, the guard-plates recessed and held against the stands, and the insulated blocks held against the ends of the contact-stands, as shown and described. 40

9. In an electric-railway system, the combination with the series of contact-stands and electrical connections therewith, the shoes, adapted to be held in contact with a stand on the outgoing and return circuits, each shoe made up of two complementary angle-plates with upturned ends, the binding-post secured to said shoe, the flanged disk, the angle-braces securing same to the shoe, the metallic post, and spring-bearing between said disk and a portion of the truck of the car carrying the 55 shoe, as set forth.

In testimony whereof I affix my signature in presence of two witnesses.

BYRON E. OSBORN.
